United States Patent Office.

S. B. MANN, OF INDIANAPOLIS, INDIANA.

Letters Patent No. 72,653, dated December 24, 1867.

IMPROVEMENT IN LAND-ROLLERS.

The Schedule referred to in these Letters Patent and making part of the same.

TO ALL WHOM IT MAY CONCERN:

Be it known that I, S. B. MANN, of Indianapolis, in the county of Marion, and State of Indiana, have invented a new and useful Improvement in Field-Rollers; and I do hereby declare the following to be a full, clear, and exact description of the same, reference being had to the accompanying drawings, forming part of this specification, and in which the drawing represents a perspective view of my invention.

In this invention the roller is a hollow cylinder, in which are placed heavy metallic balls for the purpose of increasing the weight without changing the bulk of the apparatus. The spring that supports the seat is also arranged in a novel manner.

In order that others skilled in the art to which my invention appertains may be enabled to make and use the same, I will proceed to describe it in detail.

In the drawings, A A are parts of the frame. B is the draw-beam. C C are braces to strengthen the frame and steady the draw-beam. B is the driver's foot-rest. E is the driver's seat, resting on springs e e, attached to the frame in front of the roller, at e' e', and in its rear at e'' e''. F is the roller-shaft, bearing in the frame A and draw-beam B. G G' are the rollers, and H H H are heavy metallic balls placed inside of each of the rollers, so as greatly to increase their weight without affecting in any degree their bulk, and for the further purpose of enabling the operator to graduate the weight of the rollers by inserting or removing any number of the balls. The ends of the cylindrical rollers may be closed entirely, or the spokes I I may be placed so near each other as to confine the balls within the rollers. The springs e e are simple flat springs bent over the rollers in a semicircular shape, and attached at their ends to the frame, thus forming guards to the rollers and supports and springs to the seat, and all of the simplest, cheapest, and most durable construction.

Having thus described my invention, what I claim as new, and desire to secure by Letters Patent, is—

The combination and arrangement of the hollow cylindrical rollers G G' with the metallic balls H H H, as and for the purpose specified.

S. B. MANN.
